UNITED STATES PATENT OFFICE.

JAMES L. SHARP, OF NEW YORK, N. Y.

GAS-STOVE.

SPECIFICATION forming part of Letters Patent No. 380,355, dated April 3, 1888.

Application filed July 6, 1887. Serial No. 243,484. (No model.)

To all whom it may concern:

Be it known that I, JAMES L. SHARP, of the city, county, and State of New York, have invented new and useful Improvements in Gas-Stoves, of which the following is a full, clear, and exact description.

My invention has for its object certain new and useful improvements in gas-stoves.

The invention consists, first, in a new form of burner. This burner consists of a ring having two rows of cogs or teeth, one adjacent to each edge, and in a grooved ring or gutter, upon which the cogged ring rests. Two branches of a gas-pipe enter this grooved ring or gutter, preferably diametrically opposite each other. The gas issues from the gutter between the cog-teeth, and, when ignited, burns within the ring and also on the outside of the ring, thereby forming a double flame in one burner.

The invention also consists in an air pipe or tube adapted to surround the ends of two gas-pipes, which are separated from each other, and in a perforated sleeve or diaphragm carried by the air-pipe, which sleeve surrounds the end of one or both of said gas-pipes, and also covers an opening in one side of said air-pipe. Gas enters one pipe from the other after first passing through the air-tube, and air also enters the receiving gas-pipe through the air-tube and perforated sleeve or diaphragm and mixes with the passing gas, so that when the gas is burned a blue flame will be produced. The perforated sleeve or diaphragm within the air-tube also serves to prevent ignition of the gas should it escape from the mixing-tube.

The invention also consists in details of construction, as will be more fully hereinafter set forth.

Reference is to be had to the accompanying drawings, forming part of this specification, in which—

Figure 1 is a plan view of a gas-stove embodying my improvements. Fig. 2 is a vertical cross-section on the line *c c*, Fig. 1. Fig. 3 is a detail face view of the cog-ring. Fig. 4 is a cross-section taken through the air-tube on the line *k k*, Fig. 2; and Fig. 5 is a vertical cross-section on the line *k' k'*, Fig. 1, the part B being removed.

A in the accompanying drawings represents

the body portion of a gas-stove, shown of circular form and carrying upon its top a removable utensil-rest, B; but the stove A may be of any other suitable shape, if desired.

Secured to the inner wall of the stove A is a short tube, D. The tube D receives at its outer end a gas-nipple, *a*, of smaller diameter than the tube D. The outer end of the nipple *a* is adapted to be connected to the gas-supply pipe. (Not shown.) The tube D is cut away on one side, forming an opening, *b*, for the admission of air. A perforated screen, *d*, is placed within or on the tube D and surrounds the opening *b* in the tube D. Through this gauze screen air may enter the tube D around the nipple *a*. The inner end of the tube D receives the end of a pipe, *e*, for conveying the mixture of gas and air to the burner. The ends of the nipple *a* and pipe *e* within the tube D are separated a slight distance, so that air may enter the pipe *e* from the opening *b*. The gas passes from the nipple *a* through the tube D into the pipe *e*, mixing with the air in said tube. For facility of adjustment of these parts, and to insure that the pipe *e* will be securely held by the tube D, I prefer to make the tube D in the form of a clamp. (Best seen in Fig. 4.) In this case one half of D is cast or otherwise attached to the stove-body A. The other half, *f*, is a cap held in place by screws *g*, as shown. When the tube D is made in this form and the parts *a*, *d*, and *e* are to be adjusted in the same, it is only necessary to first release the cap *f*, and after the adjustment is made the cap *f* can be drawn up again by means of the screws *g* to firmly clasp the pipe *e*; but the pipe *e* may be otherwise held, if desired. The inner end of the pipe *e* enters a cross-pipe, *h*, which is provided on its ends with two upright branches, *i i*, which enter a horizontal grooved ring or gutter, E, on opposite sides of its center. A ring, F, rests upon the hollow upper side of the gutter E, and is secured thereto by means of screws or bolts *j j*, that pass through said ring, through the upright branches *i i*, and through the lower part of the cross-pipe *h*, where they are secured by nuts, as shown, forming a ready means of attachment and detachment. The heads of the bolts sink into the ring F. By this means the ring is firmly held in position. Thus the uprights *i i* serve the double purpose of passage-way for the gas to

the burner and for the bolts to hold the ring F in position, provided on its lower face with a double row of cogs or teeth, $l^1 l^2$, which are situated along its outer and inner edges, respectively. (Best shown in Fig. 3.) The cogs or teeth $l^1 l^2$ are arranged to rest upon the upper edges of the gutter E, so as to form outlets for the mixed air and gas between them. The gutter E and ring F when placed in position form a complete burner. The mixture of gas and air issues from the gutter E between the cogs $l^1 l^2$ and the edges of the gutter E, and, when ignited, burns on the inner and outer edges of the ring F, thus producing a double flame in one burner.

The perforated sleeve d serves to prevent ignition of the gas should it escape from the mixing tube.

Having now described my invention, what I claim is—

1. The combination of the removable ring F, having the rows $l^1 l^2$ of teeth on its outer and

inner edges, respectively, the gutter E, having plain upper edges carrying said ring, the two branches $i i$ on pipe h, which enter the gutter E on opposite sides, bolts $j j$, that pass through the ring F, through the branches $i i$, and through the pipe h, and the pipes e and h, substantially as described.

2. The tube D, having side opening, b, and perforated sleeve d, combined with the pipe e and nipple a, all arranged so that air may enter the pipe e through the perforated sleeve d, while the gas enters it from the nipple a.

3. The stove-body A, having inwardly-projecting partial tube D, combined with the cap f, which completes the tube D, and with the nipple a, extending outward, and pipe e, extending inward, from said tube D, as specified.
